FISHING LURE BODY

Joseph F. Voros, 9930 Elmonte,
Overland Park, Kans. 66207

Filed Nov. 2, 1970, Ser. No. 25,761

Term of patent 14 years

Int. Cl. D22—05

U.S. Cl. D22—28

FIG. 1 is a perspective view of a fishing lure body embodying the design. The broken line portions are for illustrative purposes only.

FIG. 2 is a front elevational view thereof.

FIG. 3 is a side elevational view thereof.

FIG. 4 is a top plan view thereof.

FIG. 5 is a perspective view of a modified fishing lure body embodying the design.

I claim:

The ornamental design of a fishing lure body, as shown and described.
